(57) **CLAIM**

The ornamental design for an ignitor for charcoal briquettes with propane burner, as shown and described.

DESCRIPTION

FIG. 1 is a perspective view of a ignitor for charcoal briquettes with propane burner showing my new design;

FIG. 2 is a side view thereof;

FIG. 3 is an opposite side view thereof;

FIG. 4 is a front view thereof;

FIG. 5 is a back view thereof;

FIG. 6 is a top view thereof; and,

FIG. 7 is a bottom view thereof.
